HANGER

Joseph Goldman, Woodmere, N. Y.

Application March 1, 1939, Serial No. 259,122

4 Claims. (Cl. 223—88)

This invention relates to garment hangers and particularly to additional or auxiliary hanger means for holding a hat, cane, umbrella, scarf, tie, shirt or other article.

5 My invention contemplates the provision of a garment hanger provided with a swingable auxiliary hanger suitable for supporting a hat or other article, and with means for normally maintaining the auxiliary hanger in relatively fixed position out of the way when it is not in use and for also locking it removably in any one of a number of 10 different positions.

15 My invention further contemplates the provision of simple and efficient locking means for locking the auxiliary hanger in any of a plurality of positions, said locking means being readily unlocked to permit the auxiliary hanger to be swung into another position and to be relocked in said 20 position against undesired swinging movement thereof.

25 My invention further contemplates the provision of a garment hanger provided with a hook having a shank on which an auxiliary hanger is swingably mounted and also provided with simple cooperating means on the hangers adapted for engagement and disengagement to lock the 30 hangers removably in relatively fixed predetermined angular relation.

35 The various objects of the invention will be clear from the description which follows and from the drawing, in which:

40 Fig. 1 is a front view of my new hanger showing the auxiliary hanger locked in a position wherein a plurality of such hangers may be suspended on a bar or rod in closely adjacent relation.

45 Fig. 2 is a top plan view of the same, showing the auxiliary hanger swung into and locked in a position at right angles to the main hanger.

Fig. 3 is a similar fragmentary but enlarged view of the locking means, showing the auxiliary hanger in the position of Fig. 1.

Fig. 4 is a similar view of the same, showing the auxiliary hanger in the position illustrated 45 in Fig. 2.

Fig. 5 is a fragmentary front view of a modified form of the invention, wherein the main hanger is formed of sheet material, such as sheet metal.

Fig. 6 is a fragmentary front view of a modified 50 form of the end portion of the auxiliary hanger wherein an integral hat-engaging loop is used instead of a cap member.

In the practical embodiment of the invention which I have shown by way of example, the main hanger 10 may, as is customary, be formed of

wood or the like, being adapted to support an outer garment such as a coat or dress, as well as trousers or the like garments in a well-known manner. Suitably secured to the body 10 of the main hanger is the wire hook 11 provided with 5 the upright shank 12. Such hangers are customarily intended to be hung on hooks in a closet or on a rod or bar and are also frequently hung on the hooks of hat or coat racks. Garment hangers of this type in general use, make no provision for 10 the support of other articles on the hanger. While attempts have previously been made to provide auxiliary hanger means for the support of such articles as hats, such means as have been 15 heretofore designed for this purpose are comparatively expensive and cumbersome and require more or less skill for the manipulation thereof.

The auxiliary hanger means which I have provided, however, is simple in construction, inexpensive to manufacture and assemble, and readily manipulated to arrange it in any selected one 20 of several positions by unskilled persons, and is adapted to be locked in the position in which it is set against undesirable movement.

25 As shown, the auxiliary hanger comprises a wire member 13 terminating in a short upright locking extension or terminal part 14 preferably parallel to the shank 12 of the hanger hook, but spaced radially outwardly therefrom. Above the 30 extension 14, the wire member is twisted loosely about the shank 12 to form a plurality of turns or loops 15 loose on the shank and therefore movable easily relatively thereto in a vertical direction and also rotatable about the shank. 35 From the loops or turns 15 extends outwardly the horizontal portion 16 of the wire member to a point beyond the hook 11. The outer end portion 17 of the wire member 13 is made preferably in a semi-circular downwardly convex form, being 40 joined at its inner end by the bend 18 to the straight portion 16. At the extreme outer end of the portion 17 is provided the hat-engaging 45 cap 19, shown in Fig. 1 as being made of wood, and suitably mounted on the end of the wire member by any suitable means as by forcing the extreme end of said member into a suitable hole in the cap.

50 As best shown in Figs. 2, 3, and 4, the upper surface 20 of the main hanger 10, adjacent the shank 12, is provided with a pair of vertical holes 21 and 22, adapted to receive the extension or terminal part 14 of the auxiliary wire member. While only two of such holes are shown, it will be understood that as many holes as is found de- 55

sirable may be provided for the purpose of receiving the extension 14 and thereby to lock the wire member 13 in a selected one of a number of different positions in which the wire member is arranged angularly with respect to the main garment member 10. Said holes 21 and 22 are, therefore, spaced apart circumferentially the desired distance and are also arranged at the same distance radially from the shank 12.

10 It will be seen that in order to lock the auxiliary hanger in the position shown in Figs. 1 and 3, the member 13 is rotated until the extension 14 is in vertical alignment with the hole 21, whereafter the wire member is lowered vertically on the shank 12 until the extension 14 enters the hole, whereupon the auxiliary hanger is locked in its proper selected position. In this position, the plane of the wire member 13 is substantially coincident with the general plane of the hanger. A 20 plurality of such hangers may thereby be hung on a rod or bar without interfering with each other, and garments may be hung on such plurality of hangers in the ordinary manner. The auxiliary hangers 13, nevertheless, provide means 25 whereby additional articles may be hung from each of the hangers.

When the hanger is used by itself as on a hook or a hat rack, the auxiliary hanger is raised relatively to the hook to remove the extension 14 30 from the hole 21, whereafter the auxiliary hanger is rotated until it assumes a position in a plane at substantially right angles to the plane of the main body member 10, as is shown in Figs. 2 and 4. In this position, the auxiliary hanger is lowered to insert the extension 14 into the hole 22, whereupon the auxiliary hanger is locked in its outstanding position.

In this position, the auxiliary hanger is well adapted to support a hat, cane, umbrella, scarf, 40 or other article. When used to support a hat, the cap 19 enters into the interior of the hat while the brim engages the bends 17 and 18 and is thereby adequately supported for easy access thereto. As has been indicated, additional holes, 45 similar to the holes 21 and 22 and similarly spaced, may be provided, should it be desired to lock the auxiliary hanger in other positions. It will further be understood that while the auxiliary hanger is freely swingable on the hook 12 when unlocked, the extension 14 and the holes 21 and 22 constitute adjustable cooperating locking means for fixing the auxiliary hanger removably in any one of a number of selected positions.

In Fig. 5, I have shown my invention applied to a metal hanger. In this form of the invention, for the wooden body member 10 is substituted the sheet metal member 23 of the same general shape but provided with a horizontal flange as 24 at its top edge and a depending edge flange as 25. In the flange 24, are made a suitable number of holes as 26 similar to the holes 21 and 22 and similarly spaced apart. The extension 14 of the wire member 13 may readily be removed from and inserted into any selected one of the holes to lock the auxiliary hanger in a selected one of a number of different positions, as has been previously described in connection with Figs. 1 to 4.

In Fig. 6, I have shown the wire member 13 enlarged and bent at its extreme outer end to

form a horizontally disposed enlargement or loop as 27 designed to replace the wooden cap 19 and serving the same function. Said loop 27 is substantially circular and it is preferably arranged slightly below the highest point 28 of the bend 5 17.

It will be seen that I have provided a simple and inexpensive auxiliary hanger and adequate inexpensive locking means therefor to maintain the auxiliary hanger in a selected one of a number of positions in which the auxiliary hanger is arranged angularly with respect to the main hanger or out of the way when a number of such hangers are to be used in closely adjacent relation, and that I have provided a structure well 15 designed to meet the severe requirements of practical use.

While I have shown and described certain specific embodiments of my invention, I do not wish to be understood as limiting myself thereto, but 20 intend to claim the invention as broadly as may be permitted by the state of the prior art and the scope of the appended claims.

I claim:

1. In a garment hanger, a main garment supporting member provided with a pair of holes in its upper edge, a hook having a vertical shank upstanding from the main member, an auxiliary hanger member provided with a loop, said loop being loosely mounted on the shank for movement around the shank and for movement also longitudinally of the shank, and a terminal part on the auxiliary member beyond the loop and spaced radially therefrom the same distance as the holes and arranged to enter and leave said 35 holes to selectively lock the auxiliary member in adjustable angular relation to the main member.

2. In a garment hanger, a main member having a hole therein, a hook on the member, and an auxiliary member swingable on the hook and having a locking part thereon adapted to enter the hole to lock said members together against relative movement.

3. In a garment hanger, a main member having a plurality of holes therein, a hook having a straight shank secured to the main member, and an auxiliary wire hanger having a loop loosely mounted on the shank and terminating in an extension adapted to enter any selected one of 50 the holes to lock the auxiliary member to the main member in any one of the number of different positions.

4. In a garment hanger, a main member provided with a plurality of holes in its upper edge 55 and in predetermined radial spaced relation to the center of said main member, a hook outstanding from the center of the main member and having a straight shank, an auxiliary wire member having a downwardly convex bend therein 60 and having a straight inner portion, said inner portion terminating in a plurality of loops loosely encircling the shank, an extension from the loops parallel to the shank and at the same distance therefrom as said holes, and an enlarged 65 circular part at the outer end of said auxiliary member.

JOSEPH GOLDMAN.
